UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING MACHINE.

Application filed December 17, 1923. Serial No. 681,060.

To all whom it may concern:

Be it known that I, JOHN KIEWICZ, a citizen of the United States, and resident of Boston, county of Suffolk, State of Massachusetts, have invented an Improvement in Sewing Machines, of which the following description, in connection with the accompanying drawing, is a specification, like characters on the drawing representing like parts.

This invention relates to sewing machines of that known type which include two co-operating loopers and loop-spreading means situated beneath the work and acting alternately to take and spread loops of needle thread that are presented by a needle which penetrates the work from above. Some sewing machines of this type, especially those adapted to form stitches along the edges of a buttonhole or around an eyelet, are provided with a turret on which the loopers are mounted, the turret being constructed to turn in order to carry the stitching around the ends of the buttonhole or around the eyelet.

Sewing machines of this type which employ the two loopers are usually so constructed that it takes two downward thrusts of the needle to form each stitch. Merely as illustrating such sewing machines I will refer to United States Patents No. 862,238, August 6th, 1907, and No. 911,551, February 2nd, 1909, but I wish to state that these sewing machines are referred to merely for illustrative purposes and that the invention is adaptable for use with other sewing machines of the above type than those illustrated in the above mentioned patents.

In sewing machines having the two loopers beneath the work it is usual to support the loopers so that they can have an oscillating movement and in order that they may perform their function properly it is desirable that this oscillating movement should be a more or less irregular one, which is in proper timed relation with the movements of the needle. In all sewing machines of this type with which I am familiar this irregular oscillating movement of the loopers is derived from a rotary cam which is mounted either on the drive shaft from which the needle is operated or on some other shaft connected thereto. Where such cam is located on the drive shaft the

connections between the cam and the loopers have usually included a relatively-long lever pivoted to the frame beneath the work, a link connection between one end of the lever and the cam and a spindle connected to the other end of the lever and extending axially of the turret and connected to the loopers. Since the movement which it is desirable to give the loopers is a more or less irregular one it has been necessary in the prior constructions to use a cam having relatively-sharp curves and where the cam is located on the drive shaft said cam in its rotation has to impart movement to all the connections between the cam and the loopers, all of which connections, are, therefore, subject to the irregular movement derived from the cam. Owing to the weight and inertia of the parts comprising these relatively-long connections the speed at which they can be successfully actuated by a cam having relatively-sharp curves places a limit on the speed at which the machine can be practically operated.

It is one of the objects of my present invention to improve sewing machines of this type by providing a construction in which the parts that are moved by the cams in giving the loopers their required movement are reduced to a minimum and this is accomplished by locating the cam means on the turret close to the loopers and providing connections for operating the cam means from the drive shaft which produces a harmonic movement, such for instance, as would be produced by an eccentric or a crank shaft.

With this construction the parts which are cam actuated are of relatively-light weight and can be moved rapidly without interfering with their operation while the relatively-long connections between the looper and the drive shaft which have more weight are given a regular harmonic movement from an eccentric. This makes it possible to increase the speed at which the machine will operate without prohibitive vibration or undue wear.

In the structures shown in the prior patents the two loopers are both carried by an oscillating block which is mounted on the turret, and they have a fixed relation to each other.

In my present invention I pivot each looper separately and employ a separate cam

member for each looper. In this way each cam has parts of minimum weight to move and each cam can be designed to give its looper the proper movement.

5 In order to give an understanding of the invention I have illustrated in the drawings a selected embodiment thereof which will now be described after which the novel features will be pointed out in the appended 10 claims.

Fig. 1 is a side view of a sewing machine embodying my invention;

Figs. 2, 3 and 4 are views of the turret with the loopers mounted thereon, Figs. 2 15 and 3 showing the opposite sides of the turret and Fig. 4 showing the turret in a position at right angles to that shown in Figs. 2 and 3;

Fig. 5 is a plan view of the turret;

20 Fig. 6 is a view of the loopers and the cams for actuating them showing the loopers in the opposite position from that illustrated in Fig. 2;

Fig. 7 is a view showing a construction 25 for adjusting the cam 40;

Fig. 8 is a section on the line 8—8, Fig. 7.

In the drawings 1 indicates the bed frame of the sewing machine which supports the head 2 in which reciprocates a needle bar 3 30 carrying a needle 4. The needle bar is actuated by any suitable means, (not shown) from a driving shaft 5 which is journaled in the head.

The machine herein illustrated is intended 35 for stitching buttonholes and the loopers which co-operate with the needle are mounted on a turret 6 which is situated beneath the bed frame 1. Both the turret and the needle bar are mounted for turning movement about a vertical axis to provide for 40 stitching around the ends of the buttonhole, this turning movement being derived from a vertically-extending rock shaft 7 which carries sector gears 8, 9 meshing with gears 45 10 and 11 on the needle bar and turret respectively. The turret 6 carries the usual throat plate 12 having the sewing opening 13 through which the needle operates.

The two loopers which co-operate with the 50 needle are indicated at 14 and 15 respectively and each looper has associated with it a spreader for spreading the loop of needle thread, said spreaders being indicated at 16 and 17.

55 In the device shown in said patents one of the loopers is a thread-carrying looper which carries an under thread that is concatenated with the needle thread, the other looper being a non-thread carrying looper, and in the 60 illustrated embodiment of the invention 14 is the thread-carrying looper and 15 is the non-thread-carrying looper.

The parts thus far described are or may 65 be all as illustrated in said patents and in the operation of the sewing machine, at each

penetrating thrust of the needle 1 one of the loopers will take the loop of needle thread which is thrown out as the needle starts upwardly and hold said loop while the needle is retracted, the corresponding 70 spreader co-operating with the looper to spread the loop and to carry the spread loop into such position that at the next penetrating thrust of the needle the latter will be inserted through the spread loop of 75 needle thread, and the other looper then enters and takes a loop of needle thread as the needle is retracted, said looper and its associated spreader operating to spread said loop and carry it into position to receive the 80 needle at the next penetrating thrust. The loopers thus act alternately on successive needle loops.

In said patents the two loopers are carried by a single oscillating block which is 85 mounted on the turret so that they have a fixed relation to each other.

In the present embodiment of the invention the two loopers are mounted separately. The looper 14 and its spreader 16 are carried on an oscillating arm 18 which is pivoted to the turret at 19 while the looper 15 and its spreader 17 are carried on another oscillating arm 20 which is pivoted to the turret at 21. The two loopers are fixedly secured 90 to the arms 18 and 20 while the loop spreaders are pivotally mounted on the arms, each loop spreader having a shank 22 which is journaled in bearings 23 formed in the arms 100 18 and 20 and being acted on by a suitable spring 24 which tends to hold it in line with the looper as shown at the left in Fig. 5.

The spreaders are given their loop-spreading movements by a spreader actuator 25 which has substantially the same construction as that illustrated in the above-mentioned patents, said spreader actuator being pivotally mounted on the turret at 26 and having two arms 27 provided with cam faces 28 that act on the ends of the spreaders at the proper times in the cycle of operations all as illustrated in said patents.

The loopers are actuated from the driving shaft 5 by the following means. Mounted 115 on said shaft is an eccentric 28, the eccentric strap 29 of which has an arm 30 connected to a lever 31 situated beneath the bed frame and pivotally mounted at 32. This lever is connected to a sleeve 33 that is situated and movable axially of the turret 6. This sleeve 120 has fast thereon a member 34 which has a vertical reciprocating movement in the turret by reason of the connection above described.

Each of the arms 18 and 20 which carry 125 the loopers derive their reciprocating movement from the member 34 through suitable cam connections. The member 18 is operated through a lever 35 which is pivoted to the turret at 36 and the upper end 37 of 130

which engages a shoulder 38 formed on the arm 18. This arm 18 is acted on by a spring 39 which holds the shoulder 38 in contact with the end 37 of the lever 35. 5 The lever 35 is formed with a cam portion 40 which co-operates with a roll or pin 41 carried by the block or member 34. This cam 40 is so designed that the regular up and down movement of the block 34 due to 10 the operation of the eccentric 28 will give the arm 18 and looper 14 the proper vibrating movement to cause the looper to function correctly.

The other looper-carrying arm 20 is provided with a tail portion 42 which has a cam surface 43 thereon. Said cam surface co-operates with a roll or projection 44 carried by an arm 45 that is secured to the block 34. This looper arm 20 is also acted on by a 20 spring 46 which tends to move it outwardly and which holds the cam surface 43 in contact with the roll 44. As the member 34 rises and falls, therefore, the action of the roll 44 on the cam surface 43 together with 25 the action of the spring 46 will give an oscillating movement to the looper arm 20 and this cam 43 is also designed so that the looper 15 will be given its requisite more or less irregular oscillating movement. With 30 this construction it will be observed that the long connections 30, 31 and 33 are all actuated by an eccentric and will, therefore, have a regular harmonic movement, which is conducive to high speed operation.

35 The cam-actuated movement which is more or less irregular but which is necessary to give the loopers their proper movement is located between the member 34 and the loopers so that the parts which the cams 40 have to actuate are simply the looper arms. These parts are relatively light in weight and can be readily given any desirable irregular movement from the cams without detracting from the speed and without producing undue vibration.

In the drawings the looper 15 and spreader 17 are in the position they assume after they have entered a loop of needle thread and have spread the same and have carried 50 the loop into position to be entered by the needle at its next downward thrust. After the needle has made such penetrating thrust and begins to rise the sleeve 33 and looper actuator 34 are raised. As the roll 44 rises 55 it rides over the cam face 43 which is shaped so as to allow an immediate withdrawal of the looper 17 under the influence of the spring 46. During the first part of the upward movement of the looper actuator 60 the roll 41 rides on the vertical face of the cam 40 thus giving the looper 14 relatively little movement but as the upward movement of the looper actuator progresses the roll 41 will engage the curved face of the 65 arm 40 and will throw the looper 14 for-

wardly with a quick movement to cause it to enter the loop of needle thread. After the looper has thus engaged the loop of needle thread the spreader actuator 25 is turned to actuate the spreader 16 and cause the latter 70 to spread the loop ready for the reception of the needle at the next succeeding penetrating thrust.

When the looper actuator 34 has been moved to the upper limit of its movement 75 the position of the loopers is such as shown in Fig. 6, the needle loop now being held by the looper 14 and the spreader 16. The next downward movement of the looper actuator 34 returns the parts to the position 80 shown in Figs. 2 and 3.

The advantage of having a separate cam for each looper is that each cam may be shaped to give the corresponding looper the correct movement and as each looper is actuated by a separate cam each looper may have the movement which is best suited to its correct operation.

It will be noted that the looper 14 is actuated by a relatively-long lever 35. This 90 construction has been employed because it is desirable that the looper 14 should have a greater amplitude of movement than the looper 15 and should also have first a slow movement and then a quick rapid movement as it enters the needle loop and carries the latter into position to receive the needle. By employing the long lever 35 which is pivoted at its lower end and engages the looper at its upper end and which has the 100 cam intermediate of its ends, it is possible to get the desired movement with a cam having easy curves. In Figs. 2 and 6 the cam 40 is shown as formed directly on the lever 35 and with this construction any adjustment for the purpose of varying the timing of the looper may be secured by adjusting the member 34 vertically on the sleeve 33.

In Fig. 7 I have illustrated another embodiment of the invention wherein the cam 110 40 is formed on a cam member 70 which is adjustably secured to the lever 35, said cam member being pivoted to said lever at 71 and being adjustable relative thereto by the adjusting screw 72. The screw 72 is shown 115 as swivelled in an ear 73 extending from the member 70 and as being screw-threaded in a lug 74 rigid with the lever 35. With this arrangement the position of the cam surface relative to the lever 35 may be varied 120 thereby varying the timing of the looper 14.

For varying the timing of the looper 15 I have adjustably secured the arm 45 to the looper actuator 34, said arm having slots 60 therein in which are received clamping 125 screws 61 carried by said member 34. By adjusting the arm 45 the position of the roll 41 relative to the cam 43 may be varied thereby varying the timing of the looper 15.

The movement which the spreader actu- 130

ator 25 has is a more or less regular one so that the desirable high speed thereof can be secured by operating it from a cam on the shaft 5 although it is within my invention 5 to operate this spreader actuator by any suitable means which will move it in proper timed relation with the loopers. In the construction herein shown the spreader actuator 25 is connected by a link 47 to a collar 10 48 fast on a spindle or rod 49 that extends axially through the sleeve 33. This spindle is connected to one end of a lever 50 which is pivoted at 51, the other end of said lever being connected to a link 53 that is piv- 15 otally connected to a cam-actuated arm 54. Said arm is pivotally connected to the frame at 55 and is provided with a roll 56 operating in a cam groove 57 formed in a cam member 58 that is mounted on the shaft 5. 20 This cam operates to oscillate the spreader actuator in timed relation with the movements of the loopers.

While I have illustrated my invention herein as applied to the type of sewing machine shown in the above-mentioned patents 25 yet I desire to state that the invention is applicable to any sewing machine having the two-looper arrangement beneath the work which co-operates with the needle in 30 concatenating the thread to form stitches.

I claim.

1. In a sewing machine, the combination with a needle operating from above the work, of two loopers and loop-spreading 35 means situated beneath the work, a movable looper-actuating member beneath the work, means for giving said member a harmonic movement, and cam elements for translating said harmonic movement of the looper- 40 actuating member into an irregular motion of the loopers.

2. In a sewing machine, the combination with a needle operating from above the work, of two independently-pivoted loopers 45 and loop-spreading means situated beneath the work, a movable looper-actuating member beneath the work, means for giving said member a harmonic movement, and means for translating said harmonic movement of 50 the looper-actuating member into an irregular motion of the loopers.

3. In a sewing machine, the combination with a needle operating above the work, of a turret situated beneath the work, two 55 loopers and their loop spreaders carried by the turret, a reciprocating looper-actuating member on the turret and cam elements for actuating the loopers from said member.

4. In a sewing machine, the combination with a needle operating above the work, a turret situated beneath the work two independently-pivoted loopers and their spreaders carried by said turret, a reciprocating 65 looper-actuating member mounted on the

turret, and cam devices for actuating the loopers from said member.

5. In a sewing machine, the combination with a needle operating above the work, of a turret situated beneath the work, two 70 loopers carried by the turret and mounted for movement independently of each other a looper spreader co-operating with each looper, a looper-actuating member movably mounted on the turret, and cam elements 75 for actuating the loopers from said looper-actuator member.

6. In a sewing machine, the combination with a needle operated from above the work, of a turret situated beneath the work, two 80 loopers carried by the turret, a reciprocating looper-actuator member on the turret, cam devices for actuating said loopers from said looper-actuating member, a loop spreader associated with each looper, and means 85 independent of the looper-actuating mechanism for operating the spreaders.

7. In a sewing machine, the combination with a needle operated from above the work, of a turret situated beneath the work, two 90 independently-pivoted loopers and their spreaders mounted on the turret, one of said loopers having an extension provided with a cam surface, a lever pivoted to said turret for operating the other looper, said 95 lever having a cam surface, and a looper-actuating member mounted on the turret and engaging said cam surfaces.

8. In a sewing machine, the combination with a needle, of a drive shaft by which 100 the needle is operated, a turret, two loopers and their spreaders mounted on the turret, an eccentric mounted on the drive shaft, means for operating both of said loopers from said eccentric, said means including 105 cam elements on the turret.

9. In a sewing machine, the combination with a needle, of a drive shaft for operating the needle, a turret situated beneath the work, two independently-pivoted loopers 110 and their spreaders mounted on the turret, a lever pivoted to the frame, an eccentric on said drive shaft for operating said lever, a looper-actuating member mounted on the turret, and operatively connected to said lever, and cam elements for translating the movement of said member into loop-taking movements of both of the loopers.

10. In a sewing machine, the combination with a needle, of a drive shaft for operating the same, a turret situated beneath the work two independently pivoted loopers and their spreaders mounted on the turret, a sleeve situated and movable axially of the turret, an eccentric on said drive shaft by 120 which the sleeve is given a harmonic movement, and cam devices for translating the harmonic movement of the sleeve into irregular loop-penetrating movements of the 125 loopers.

11. In a sewing machine, the combination with a needle operated from above the work, of two independently-pivoted loopers beneath the work, a turret on which said loopers are mounted, a lever pivoted at one end to the turret and having its other end operatively connected to one of the loopers, said lever having a cam surface intermediate of its ends, a looper actuator member mounted on the turret and engaging said cam surface, means for giving the actuator a harmonic movement, and means to operate the other looper from said actuator.

In testimony whereof, I have signed my name to this specification.

JOHN KIEWICZ.
